UV-C LEDs fan out in air circulation offerings, date posted Dec. 4, 2020, site visited Dec. 31, 2022, available from internet <<https://www.ledsmagazine.com/lighting-health-wellbeing/article/14188485/uvc-leds-fan-out-in-air-circulation-offerings>>.*

Primary Examiner — Sharon S Oum

(74) Attorney, Agent, or Firm — Dickinson Wright PLLC;
 Andrew D. Dorisio(57) **CLAIM**

The ornamental design for a lighting module for a fan, as shown and described.

DESCRIPTION

FIG. 1 is a top perspective view of my design for a lighting module for a fan;

FIG. 2 is a top perspective view of the lighting module;

FIG. 3 is a front view of the lighting module;

FIG. 4 is a left side view of the lighting module;

FIG. 5 is a rear view of the lighting module;

FIG. 6 is a right side view of the lighting module;

FIG. 7 is a top view of the lighting module; and,

FIG. 8 is a bottom view of the lighting module.

The broken lines illustrate portions of the lighting module for a fan and environmental structure. None of the broken lines form part of the claimed design.

1 Claim, 8 Drawing Sheets(56)
